[57] CLAIM

The ornamental design for a body of an armored land vehicle, as shown and described.

DESCRIPTION

FIG. 1 is a right side elevational view of a body of an armored land vehicle showing my new design;

FIG. 2 is a left side elevational view thereof;

FIG. 3 is a rear elevational view thereof;

FIG. 4 is a front elevational view thereof; and

FIG. 5 is a top plan view thereof.

The broken lines in the drawing are for illustrative purposes only.
